UNITED STATES PATENT OFFICE.

LEVI K. FULLER, OF BRATTLEBOROUGH, VERMONT, ASSIGNOR TO J. ESTEY
& CO., OF SAME PLACE.

DESIGN FOR THE ENDS OF AN ORGAN-CASE.

Specification forming part of Design No. 6,678, dated May 27, 1873; application filed April 25, 1873.

To all whom it may concern:

Be it known that I, LEVI K. FULLER, of Brattleborough, in the county of Windham and State of Vermont, have invented a Design for an Organ-Case, of which the following is a specification:

In the accompanying photographic illustration, to which reference is made, my design is fully represented; and it consists in the form of a pilaster arranged near the central portion of the ends of the case, and extending from the base to the top.

In the accompanying illustration, B B is the end of the case, and A the pilaster, situated near the center of the same, as shown, its general surface being on a plane parallel with that of the end. It is connected with the base

by a curve or molding, and expanded at the top into the semblance of a capital. By this means an agreeable architectural effect is imparted to the ends of the case.

I claim as my invention—

The design for the ends of an organ-case, consisting of the pilaster A, in combination with the ends B B, substantially as shown and described.

In witness whereof I have hereunto signed my name in the presence of two subscribing witnesses.

LEVI K. FULLER.
